[57] ABSTRACT

An innersole forming strip from which innersoles can be prepared suitable for use in a wide variety of shoe styles and sizes by transverse alternate direction die-cutting. The strip is formed by skiving fiberboard on one surface with two bands spaced on either side of a non-thinned central band.

FIG. 5

FIG. 6

INNERSOLE FORMING STRIP

BACKGROUND OF INVENTION

This invention relates to a novel innersole forming strip and a method and apparatus for its formation. The strip is die-cut into a plurality of finished innersoles.

In the manufacture of innersoles, particularly in the case where they are to be used in cemented sole constructions, the innersole must have different properties in its various portions. Thus, the heel portion should be rigid and relatively thick and the shank portion rigid and relatively thick. However, the forepart or ball portion should be flexible and relatively thin.

The ball, or forepart, while being flexible, must also have sufficient lateral stability to withstand the pressure exerted during the lasting operation without buckling. This is necessary to provide a well defined line in that area to facilitate later shoemaking operations and assist in the provision of a tailored finish and shape retention qualities during wear. Graduation from one thickness of material to another must be smoothly contoured.

One conventional method of making such structured innersoles is to combine various materials of suitable specification in their appropriate locations. These are applied together, which procedure involves lap skiving, cementing and assembling of each piece. When the size and style ranges required are taken into consideration, considerable inventory of various pieces is involved. In practice this conventional method has disadvantages such as labor cost and the utmost precision required to assemble the pieces so that the splice as made is absolutely smooth. By reason of the difficulty of providing smooth assembly of the pieces, ledges and bumps are common which result in bumpy bottoms on the shoes, discomfort to the wearer, broken socklinings after wear and splices breaking down. Also, in order to provide lateral stability at the ball or forepart section, expensive flexible material must be used.

Another conventional method comprises skiving a single sole innersole blank of suitable material, making an innersole which is built in good shoes piece by piece as the shoe is made.

One object of this invention is to provide a novel innersole forming strip which is so constructed that only die-cutting is required to provide a plurality of finished innersoles each having the desired properties in its various portions.

A further object of this invention is to provide such an innersole forming strip which uses a minimum of expensive materials such as flexible plastic with a maximum of inexpensive material such as fiberboard to yield high quality innersoles of desired construction and dimensions.

Further objects and advantages of this invention will be apparent from the description and claims which follow and from the appended drawings.

BRIEF DESCRIPTION OF DRAWINGS

FIG. 1 is an oblique top view of the apparatus of this invention.

FIG. 2 is a plan view of the under surface of the fiberboard strip after it emerges from the apparatus.

FIG. 3 is a transverse section along line 3-3 of FIG. 2, slightly enlarged.

FIG. 4 is a plan view of a sole which has been die-cut from the strip illustrated in FIG. 2.

FIG. 5 is an elevation of the sole illustrated in FIG. 4.

FIG. 6 is an elevation of a sole similar to that illustrated in FIGS. 4 and 5 but which has been subsequently treated on the other surface with slashing as shown in phantom.

SUMMARY OF INVENTION

The invention comprises generally forming an innersole forming strip from which a plurality of innersoles can be prepared suitable for use in a wide variety of shoe styles by transverse, alternate direction die-cutting. The innersole forming strip comprises an integral, non-spliced strip of fiberboard which is flat on one surface and has on the opposite

surface two longitudinally uniform thinned bands in the potential forepart sections spaced on either side of a non-thinned central band. The non-thinned central band registers with the shank and heel portions of the alternately oriented die-cuts.

5 The width of the strip of fiberboard is approximately that of the composite length of two alternately positioned soles nesting in the shank and heel sections. The thinned bands of potential forepart sections are formed by skiving one surface of the fiberboard strip. Where even greater flexibility is desired than that provided by thinning, the portion of the opposite surface which registers with the thinned portion is slashed.

The specifications of the innersole determine the specifications of the innersole forming strip. Where exceptional flexibility is required, a longitudinal strip of thin flexible material such as plastic or foam rubber is adhered to the first or non-skived surface in selected locations, usually including the forepart region. After the innersole forming strip of this invention 15 has been made, the only operation required to form a plurality of finished soles is the alternate die-cutting. In this fashion, a shoe manufacturer may buy one type of innersole forming strip and use it to produce a plurality of sizes, shapes and designs of innersoles merely by having the appropriate dies.

20 The apparatus especially preferred for the present invention comprises a frame, a pair of rotatable rolls including an upper matrix roll and a lower feed roll and a knife assembly positioned adjacent to the output side of the bite of the rolls and cooperating with the matrices on the upper or matrix roll and the feed roll to skive the fiberboard sheet in two bands. Where 25 slashing is desired to increase flexibility, the apparatus includes a second pair of rolls beyond the skiving area which include a bottom feed roll and an upper cutting roll having a plurality of slashing blades registering on the opposite surface to the thinned, skived bands. This upper roll can also have protuberances for embossing peripheral pinpoints or recesses in the potential toe portions to aid in adhesion of the upper to the inner sole. Such apparatus can be used for thick as well as thin 30 sheets of fiberboard and can be adapted for toe skiving, where desired, by using a matrix and knife along the potential toe section bands.

SPECIFIC EXAMPLE OF INVENTION

35 Referring now to the drawings, there is illustrated therein an apparatus 10 comprising a frame 11 supporting a motor and gear box 12, matrix roll 30, cooperable with feed roll 40. The matrix roll 30 comprises matrices 35 and 36 held in position by locking rolls 31 and 32 and 33 and 34 respectively. The roll 40 is held in place by mounting member 17 extending through support block 27.

In front of the pair of rolls 30 and 40 is a knife assembly 50 which includes a pair of blades 20 and 21 which are arranged to be adjustably co-acting with the matrices 35 and 36. The adjustments comprise threaded vertical rods 18 and 19, which are attached to base plate 22 as well as longitudinal slots in the knife blades 20 and 21 cooperating with nuts 20a, 20b, 21a and 21b.

60 Forward of the knife and matrix assemblies are a pair of rolls 45 and 52 supported on blocks 55 and 56. Upper block 45 contains slashing roll 50 and slashing roll 51, each held by spacers 46 and 47 and 48 and 49 and containing cutting edges 50a and 51a adapted to slash the upper surface of the fiberboard 23 which is passing through the machine. The finished board is carried away on a belt 13 actuated through a pulley 14.

A sheet of fiberboard 23 enters the machine from the rear, being guided by brackets 24 and 25 and has its under surface 70 skived by the combination of the knife blades 20 and 21 in conjunction with the matrices 35 and 36. As it passes further its upper surface is slashed at 23b and 23c by the cutting blades 50a and 51a of the slashing roll. When the board is not slashed but only skived, it is designated as 29 with the under, skived surface being designated as 29a and 29b. In the case of

the strip which has been both skived and slashed, the under surface which is skived is designated as 23d and 23e.

Referring now to FIGS. 2, 3 and 4, innersole forming strip 29 has longitudinal skived bands 29a and 29b. The phantom outlines 53 and 54 show the alternate, nesting position for die-cutting wherein the forepart areas are in the skived zones while the shank and heel areas are in the central, unskived bands. Sole 57 which has been cut from the forming strip 29 comprises, as a result, an unthinned shank and heel portion 60, a thinned and hence flexible forepart section 59 and an unthinned toe portion 58.

As illustrated in FIG. 6, a sole 157 which has been slashed in addition to being skived comprises an unthinned shank and heel portion 160, an unthinned toe portion 158 and a thinned forepart section 159 having slashes 161 on its opposite surface.

What is claimed is:

1. A method of producing an innersole forming strip comprising forming an integral, non-spliced strip of fiberboard whose width is approximately that of the composite length of two alternately positioned soles nesting in their shank and heel sections, and skiving one surface of the strip longitudinally on both potential forepart sections so as to form two thinned

bands on either side of a non-thinned central band.

2. The method of claim 1 wherein as an additional step the portion of the opposite surface registering with said thinned bands is slashed.

5 3. An apparatus for producing an innersole forming strip comprising:

- a frame (11);
- a pair of rotatable rolls comprising an upper roll (30) and a lower roll (40); said upper roll (30) having a matrix (35, 36) on each side and said lower roll (40) being a feed roll, said rolls being adapted to receive and pull through a sheet of fiberboard (23), and
- c. a knife assembly (20) adapted for cooperation with said matrices and feed roll to skive said sheet (23); a second pair of rotatable rolls, namely an upper roll (45) and a lower feed roll (52) being positioned beyond said knife; said upper roll (45) having portions adapted to slash or emboss said sheet (23).

20 4. The apparatus of claim 3 wherein said upper roll (45) has a pair of cutting sections (50a and 51a) adapted to slash said sheet (23) on the surface opposite the skived portions.
